UNITED STATES PATENT OFFICE

EARNEST C. CRYPE, OF GOSHEN, INDIANA

LIGHTNING ROD COUPLER

Application filed July 10, 1929. Serial No. 377,303.

This invention relates to a coupler for lightning rods, one of the objects being to provide coupling members which can be applied to the ends of lightning rod sections in such 5 away as to form an intimate contact between the parts and to prevent them from separating except by severing the parts.

With the foregoing and other objects in view which will appear as the description 10 proceeds, the invention resides in the combination and arrangement of parts and in the details of construction hereinafter described and claimed, it being understood that changes in the precise embodiment of the invention 15 herein disclosed may be made within the scope of what is claimed without departing from the spirit of the invention.

In the accompanying drawings the preferred form of the invention has been shown.

20 In said drawings,

Figure 1 is a perspective view of a section of lightning rod showing a coupling member connected to each end thereof.

Figure 2 is a similar view showing the 25 coupling members prior to being applied to the section of the lightning rod.

Figure 3 is a section showing two of the coupling members joined, one of the coupling members being crimped into permanent 30 engagement with one lightning rod section while the other coupling member is shown in position on its rod section prior to crimping.

Figure 4 is an end view of one of the 35 coupling members.

Figure 5 is a section on line 5—5, Figure 3.

Referring to the figures by characters of 40 reference, 1 designates a lightning rod section formed of the usual spiral ribs extending in the direction of its length, each end of the section 1 being formed with a transverse lip 2 which serves to close opposed spaces between the ribs thereby to produce pockets 3.

The coupling for use with each rod section 45 is formed of two members indicated at 4 and 5 respectively. The member 4 has an angular recess 6 extending thereinto from one end for the reception of one end of the rod 1, the inner end of this recess being provided with reinforcing lugs 7 that extend to

ward each other from opposed walls and serve to reinforce the coupling where the walls of recess 6 join the remaining portion of the coupling. Another recess 8 is extended into the other end of the coupling member 4 and has its wall screw-threaded as shown particularly in Figure 3.

The other coupling member 5 is provided with a screw-threaded stub 9 that extends from one end thereof while an angular recess 60 similar to the recess 6 is formed in the other end thereof and adapted to receive one end of the lightning rod section 1.

After coupling members 4 and 5 have been applied to the opposed ends of a lightning rod section so that the lips 2 thereof will extend between the lugs 7, the walls of said members 4 and 5 are crimped or pressed inwardly so as to bear within the angles formed between those portions of the 65 ribs of the rods located in the recesses. As some of these inwardly pressed portions or crimps will extend into the pockets 3 it will be obvious that after the crimping operation it will be impossible to remove the members 4 and 5 from the rod and an intimate contact between the parts is insured under 70 all conditions.

Rods with the coupling members such as 75 described may be joined end to end by 80 screwing the studs 9 into the recesses 8.

What is claimed is:

1. The combination with a rod having longitudinal ribs and means at the ends of the rod for closing the ends of the spaces between the ribs, thereby to form pockets, of coupling members having recesses into which the respective ends of the rod project, the walls of the recesses being pressed into the pockets to hold the rod against withdrawal 85 from the recesses, and means carried by the coupling members for joining them to other elements.

2. The combination with a lightning rod having ribs joined at one end to form a pocket, of a coupling member having a recess in which said pocket is seated, said recess having a wall depressed into the pocket to prevent withdrawal of the rod from the recess.

3. The combination with a lightning rod or the like having longitudinal ribs, of a lip extending across one end of the rod and closing the spaces between the ribs to provide pockets, a coupling member having a recess, opposed lugs in the recess, said lip being seated between the lugs and the pockets concealed in the recess, opposed walls of the recess being compressed into the pockets to hold the rod and coupling against separation.

In testimony that I claim the foregoing as my own, I have hereto affixed my signature.

EARNEST C. CRIPE.
